BASE FRAME FOR RECLINING CHAIR

William P. Taylor, Glencoe, Ill., assignor to Burris
Industries, Incorporated, Lincolnton, N.C.

Filed Nov. 9, 1973, Ser. No. 414,593

Term of patent 14 years

Int. CL. D6—06

U.S. CL. D6—194

FIG. 1

FIG. 2

FIG. 3

FIG. 4

FIG. 5

FIG. 6

FIG. 1 is a perspective view of the base frame for reclining chair embodying my new design as seen from above the left front end thereof;

FIG. 2 is a side elevational view of the base frame for reclining chair;

FIG. 3 is a front elevational view of the base frame for reclining chair;

FIG. 4 is a top plan view of the base frame for reclining chair;

FIG. 5 is a rear elevational view of the base frame for reclining chair; and

FIG. 6 is a bottom plan view of the base frame for reclining chair.

I claim:

The ornamental design for a base frame for reclining chair, substantially as shown.
